John F. Packer

UNITED STATES PATENT OFFICE.

JOHN F. PACKER, OF CHICAGO, ILLINOIS, ASSIGNOR TO HIMSELF AND
J. HARLEY BRADLEY, OF SAME PLACE.

DESIGN FOR A RADIATOR.

SPECIFICATION forming part of **Design No. 18,784**, dated **December 4, 1888**.

Application filed October 27, 1888. Serial No. 289,346. Term of patent 14 years.

To all whom it may concern:

Be it known that I, JOHN F. PACKER, a citizen of the United States, residing at Chicago, in the county of Cook and State of Illinois, 5 have invented and produced a new and original Design for a Radiator for Steam and Hot-Water Heating Apparatus, of which the following is a specification, reference being had to the accompanying drawing, forming part 10 thereof.

The figure is a front elevation of a radiator showing my design.

The leading feature of my design consists in a radiator which represents parts of trees, 15 such as the trunk, limbs, knots, and bark.

A A are, in effect, the posts or uprights of the radiator, located one on each side thereof, the same being conventionalized representa-

tions of the trunk of a tree or a large limb of a tree. 20

B is the central portion of the radiator, which is composed of a number of conventionalized representations of various parts of trees, such as limbs, knots, bark, &c.

This design for a radiator presents a rustic 25 appearance that is quite attractive.

What I claim is—

The design for a radiator herein shown and described, the parts A B of the same being conventionalized representations of parts of 30 trees, as set forth.

JOHN F. PACKER.
